UNITED STATES PATENT OFFICE

THOMAS W. CASEY, OF AKRON, OHIO, ASSIGNOR TO SEIBERLING LATEX PRODUCTS COMPANY, OF BARBERTON, OHIO, A CORPORATION OF OHIO

DESIGN FOR A HOT-WATER BOTTLE

Application filed April 28, 1930. Serial No. 35,400. Term of patent 7 years.

To all whom it may concern:

Be it known that I, THOMAS W. CASEY, a citizen of the United States, residing at Akron, in the county of Summit and State of Ohio, have invented a new, original, and ornamental Design for a Hot-Water Bottle, of which the following is a specification, reference being made to the accompanying drawings, forming a part thereof.

Of the accompanying drawings, Fig. 1 is

a front elevation of the upper portion of a hot water bottle showing my new design.

Fig. 2 is a rear elevation thereof.

Fig. 3 is an edge view partly in section on the line 3—3 of Fig. 1.

I claim:

The ornamental design for a hot water bottle as shown.

THOMAS W. CASEY.
